2 SHEETS—SHEET 2.

UNITED STATES PATENT OFFICE.

LE ROY STEWART FOLTZ, OF FORT COLLINS, COLORADO.

BURGLAR AND FIRE ALARM.

1,373,495.

Specification of Letters Patent.

Patented Apr. 5, 1921.

Application filed February 4, 1919. Serial No. 274,879.

To all whom it may concern:

Be it known that I, LE ROY S. FOLTZ, a citizen of the United States, and a resident of Fort Collins, in the county of Larimer and State of Colorado, have invented a new and useful Improvement in Burglar and Fire Alarms, of which the following is a specification.

My invention relates to improvements in burglar and fire alarms, and it consists in the constructions, combinations and arrangements herein described and claimed.

An object of my invention is to provide a burglar and fire alarm which is in the nature of an attachment to the ordinary telephone system, the burglar and fire alarm being so arranged to apprise the central office or a neighbor's house of the presence of an intruder, without the knowledge of the intruder, or in the presence of a fire.

Another object of the invention is to provide a burglar and fire alarm as described, including as one of the important features, an automatically operating receiver hook elevator with a contact making device, for sending signals over the telephone line.

A further object of the invention is to provide a burglar and fire alarm as described, by means of which the particular call of the party whose premises are invaded or otherwise endangered, is sent over the line to neighboring telephones in rural communities, any person then "listening in" hearing a separate warning signal between rings and thus being apprised of the danger in the first party's premises.

Other objects and advantages will appear in the following specification, reference being had to the accompanying drawings in which:

Figure 1 is a diagram illustrating the application of the burglar and fire alarm to an ordinary common battery telephone instrument used in the city.

Fig. 2 is a diagram illustrating the application of the burglar and fire alarm to a local battery telephone used in rural districts.

Fig. 3 is a front elevation of the automatically operating receiver hook elevator.

Fig. 4 is a side elevation thereof, parts being shown in section.

Fig. 5 is a detail view of the contact surface gear; and

Fig. 6 is a view of the reverse side of the gear 23, showing contact hereinafter described.

By way of preface, it is desired to state that the burglar and fire alarm about to be described, operates to apprise either the central or telephone operator at a central station, or some other persons, of the presence of an intruder or of some other abnormal condition in a protected premises, without sounding an alarm in the premises thus protected, and consequently not alarming the intruder and frightening him away. Those duly authorized to do so, then apprehend the intruder or investigate the abnormal condition; the sounding of the alarm and the approach of the investigators having taken place altogether without the knowledge of the intruder, or any alarm being sounded on the endangered premises.

Now in carrying out my invention, I provide parallel wires 1 which are led throughout or over a protected premises. Connected in parallel across the wires 1 is a plurality of contacts 2 which are of course normally open. The contacts 2 are located at different points about the building, as for instance, at a window or at a door as illustrated in Fig. 1.

The contacts 2 conventionally represented in Figs. 1 and 2 of the drawings, will in practice be so constructed that they may be readily concealed at the points to be protected, and may also consist of thermally operated contacts so designed to set the alarm into operation upon the breaking out of a fire on the premises. Without further description, it will be understood that the wires 1 are trained over the house if such is to be protected, with the contacts 2 at every point likely to be attacked by an intruder, whereupon on closing one of the contacts 2, the alarm is set into operation, as will presently appear.

Located in a branch 3 of one of the wires 1, is a control switch 4 which is moved over into the position illustrated in Figs. 1 and 2, to close the circuit with the exception of the portions thereof terminating at the contacts 2. A battery 5 is partly embraced by the

branch 3. One of the wires of the branch is connected to the positive pole of the battery, while the other wire of the branch 3 is connected to a negative pole about mid-way of the battery.

One terminal of the motor 6 of the automatically operated receiver hook elevator, is connected to the negative pole of the battery 5 by a wire 7. The reason for connecting one of the wires of the branch 3 to a negative pole about mid-way of the battery 5 is, to obtain a sufficiently low current for the operation of a relay 8 connected in series with the parallel wires 1.

The relay 8 includes a contact 9 against which the armature 10 of the relay is arranged to strike upon energization of the relay. When the armature 10 is thus attracted, current flows from the positive pole 20 of the battery 5 through the contact 9, armature 10 and over the wires connected to the motor 6 of the receiver hook elevator.

A few initial turns of the motor 6, or rather of the shaft of the motor, serve to 25 elevate the receiver hook 11 into the talking position. The construction of the receiver hook elevator is best illustrated in Figs. 3 and 4, to which attention is directed. Here it will be observed that the shaft 12 of the 30 motor 6 carries a worm pinion 13 which is threaded into a worm socket 14 on the end of a square shaft 15.

Fitted over the end of the square shaft 15 is the socket 16 of a plunger 17 which contacts the lower edge of the receiver hook 11, as shown in Figs. 1 and 2. A spring 18 is located in the socket 16 ahead of the square shaft 15, as shown in Fig. 4. The spring 18 compresses to a certain extent on the upward movement of the square shaft 15 and thus provides a yielding connection between the plunger and the shaft. The shaft 17 carries a collar 17^a which is arranged to engage terminals 17^b that are connected to the lead wire of the local receiver and short circuit the receiver when the collar rises into engagement with the terminals.

Brackets 19 fixed on the base 20 of the receiver hook elevator, provide supports or 50 bearings for the respective shafts 12 and 15. It will be readily understood that as stated before, a few initial turns of the motor 6 will cause the square shaft 15 to rise in the brackets 19 through the action of the worm pinion 13 in the worm socket 14, and consequently cause the plunger 17 to lift the receiver hook 11 into the talking position. Incidentally it should be understood that Figs. 3 and 4 show the square shaft 15 and plunger 60 17 in the extended position.

This being the case, the worm socket 14 has been lifted or forced out of threaded engagement with the worm pinion 13. The connection between the work socket 14 and 65 the worm pinion 13 is however, not broken.

The threads in the socket 14 terminate a short distance from the open end of the socket, the bore of the socket being made smooth or threadless, as indicated at 21. This threadless portion of the bore of the 70 socket 14 provides a recess which is occupied by the end of the worm pinion 13 when the threaded portion of the socket is turned completely out of engagement with the worm pinion 13. Upon resetting the device, the 75 shaft of the motor is simply counter-rotated by hand so that the worm pinion 13 again screws into the socket 14 and the square shaft 15 with the plunger 17, is lowered to the original or normal position.

Fixed on the motor shaft 12 is a pinion 22 which meshes with a gear 23 journaled in a bracket 24. The face of the gear 23 on one side, has an arrangement of contacts 25 against which brushes 26 on an arm 27 bear. 80 The arrangement of the contacts 25 is shown in Fig. 5 and the purpose of the contacts is to send a succession of impulses through the transmitter circuit, and line when the motor 6 is in operation as just described. 90 These impulses repeatedly short circuit the transmitter and as soon as the central operator answers the apparent call, she will receive a distinct and understandable signal, telling her that a condition exists on the 95 premises from which the signal comes, which requires investigation.

Referring to Figs. 1 and 2, it will be observed that the brushes 26 are joined with the wire connections of the transmitter 28 through wires 29. The arrangement of the telephone instrument connection, is on a well known order, the arrangement in Fig. 2 being, however, slightly different from that which is shown in Fig. 1. The rural telephone in Fig. 2 includes a local battery and when the motor 6 is operated upon closure of one of the contacts 2, a magneto 30 operated by an extension of the motor shaft 12, sends a ringing current over the main line 110 through the wires 31 connected between the main line and the magneto. This ringing current is made to consist of a certain signal that is produced by suitably spaced contacts 25^a, occupying one-half of the circumference 115 on the other side of the gear 23.

A normally closed relay 32 is embraced in one of the wires 7 leading to the motor 6 from the armature 10 of the relay 8. Upon energization of the relay 8, current from the positive pole of the battery 5 flows over the wire 3 to the contact 9, through the armature 10 and the windings of the relay 32, through the motor 6 and back to the negative pole of the battery 5. The relay 125 32 being energized, the armature of the relay is drawn down opening the portion of the telephone circuit normally closed thereby. With the exception of the inclusion of the relay 32 and the ringing magneto 30, 130

the arrangement of the burglar alarm circuit in Fig. 2 is the same as that illustrated in Fig. 1, and operates in the same manner.

As formerly pointed out, the contacts on 5 the gear 23 in the arrangement of the rural telephone in Fig. 2, are so placed to alternately ring a certain signal and produce an alarm sound in the receiver at stated periods. For example, if an alarm proceeds 10 from a protected premises, the signal on this premises will sound in the neighboring houses along the line. The alarm is intended to sound in rapid succession and naturally the neighbors will "listen in", 15 whereupon they would hear the special alarm signal produced by the contacts 25 on one side of the gear 23. The signal itself is conveyed to the telephone line by the second set of brushes 26^a with which the 20 wires 31 connect.

While the construction and arrangement of the burglar and fire alarm is thought to be fully understood from the foregoing description, a brief review thereof, together 25 with an exposition of the advantages, is thought to be of value. In the normal position of the parts, the worm socket 14 is screwed completely down upon the worm pinion 13 so that the worm pinion is concealed in the socket. The plunger 17 will be in the lowermost position, while the weight of the receiver on the hook 11 bears it down in contact with the end of the plunger 17. The wires 1 are led over the premises and one of the normally open contacts 2 is located at every point which it is desired to protect. The main or control switch 4 is closed as shown in Figs. 1 and 2.

Should an intruder now open a window 40 or door as shown in Fig. 1, the pair of contacts 2 located at this point will be moved into engagement and close the circuit. The relay 8 is energized attracting the armature 10 into engagement with the contact 9 45 whereupon the motor 6 is also energized. The rotation of the motor shaft 12 unscrews the worm pinion 13 from the socket 14 and elevates the square shaft 15 so that the plunger 17 presses the receiver hook 11 up into 50 the talking position. At the same time, the gear 23 is rotated by means of the pinion 22 on the motor shaft 12, and a series of impulses are sent over the line, which when received by the central operator, will give 55 her to understand that an abnormal condition exists in the protected premises. The central operator may then notify the proper authorities. On the rural telephone line all of the bells of the neighbors on that line 60 repeatedly ring the call of the home in trouble.

One of the principal advantages of this alarm is, that no local alarm whatever is given to warn the intruder that the premises

are protected and that his presence is being 65 detected. The intruder is thus not frightened away and will remain on the premises until his captors approach and apprehend him. In the event that the contacts 2 are so arranged as to be closed in the event of 70 a fire, the same operation is carried out and the investigators are promptly brought to the scene.

It should be observed that every telephone 75 may be easily converted into a guarding device at an expense approximately equal to that of another telephone instrument. The advantages derived from the use of the device at a comparatively low cost, will completely offset such cost and make the installation of the alarm popular. The ordinary use of the telephone is not interfered with in any way, whether the main or control switch 4 is open or closed. An intruder's uncertain knowledge whether or 80 not the premises he is about to enter is guarded with an alarm as described, which gives no local indication of its presence, but does sound the alarm at the central station, will make the profession of burglary more 85 90 dangerous to those who practice it and will thus tend to decrease attempts at robbery.

While the construction and arrangement 95 of the burglar alarm as illustrated in the accompanying drawing is that of a generally preferred form, obviously, modifications and changes may be made without departing from the spirit of the invention or the scope of the claims.

I claim:

1. A burglar and fire alarm comprising in combination with an electrical circuit, a contact arranged to be closed, a contact carrying member arranged to be moved upon closure of said contact to move said contact carrying member, contacts suitably arranged on one part of said carrying member to periodically send call signals over the electric circuit from the endangered premises, a telephone transmitter included in the aforesaid 100 combination, and suitably arranged contacts in another part of said carrying member to intermittently short circuit the transmitter between the aforesaid signal period, and issue a distinct warning in other receivers connected along said electric circuits. 105 110 115

2. The combination in a burglar and fire alarm, of a receiver hook, an operatively associated electrical circuit with closable contacts, and an electro-motively and screw-actuated plunger, extensible by operation of the motor and screw to lift the hook while the receiver is on, upon energization of said device by the closure of a contact. 120

3. In a burglar and fire alarm, a contact, a 125 source of electrical energy, a relay in circuit with said source and said contact, to be energized upon closure of said contact, and re-

ceiver hook elevating means including an extensible plunger adapted to engage the receiver hook to move it to the talking position and a motor arranged to be energized upon 5 energization of said relay, said motor being arranged to extend said plunger upon operation thereof.

4. In a burglar and fire alarm, the combination with the receiver hook, of an extensible member for lifting the hook to the talking position, a motor arranged upon energization to move said extensible member, a source of electrical energy in circuit with the motor, a relay controlling the closure of said 10 circuit through the motor, and a contact in circuit with said relay and a portion of said source of electrical energy, arranged upon closure to energize said relay to operate the motor.
- 15 5. In a burglar and fire alarm, the combination with a receiver hook and transmitter, of an extensible member arranged to lift the receiver hook to the talking position, a motor for moving said extensible member upon energization, a short circuiting device in connection with the transmitter and actuated upon operation of the motor to issue a warning to a central station without producing local sounds, a source of electrical energy in 20 circuit with the motor, a relay arranged to control said motor circuit, and a contact in circuit with a portion of said source of electrical energy and said relay, to energize said relay upon closure of the contact and render 25 the motor operative.

6. In a burglar and fire alarm, the combination with a receiver hook, of an extensible plunger engaging the receiver hook, a non-circular shaft received by one end of the 30 plunger, a bracket supporting said shaft and holding it from turning, a motor including a screw connection between the motor shaft and the non-circular shaft arranged to extend the non-circular shaft and 35 the plunger upon rotation of the motor shaft, a source of electrical energy in circuit with the motor, a relay arranged upon energization to close the motor circuit, and a contact in circuit with a portion of said electrical energy and said relay, to energize the 40 relay upon closure of the contact and operate the motor.

7. In a burglar and fire alarm, means arranged to contact the receiver hook of a telephone instrument, said means having a recess at the free end, a non-circular shaft projecting into the recess, a resilient member between the end of the shaft and the base of the recess, means supporting the non-circular 45 shaft and holding it from turning, an internally threaded worm socket on the free end of the non-circular shaft, a portion of the threads in the socket being removed to leave a smooth recess, a motor having a 50 motor shaft, and a worm pinion normally

screwed into the internally threaded socket, the worm pinion being adapted to unscrew from the socket and project the non-circular shaft and hook contacting means to the extended position and raise the receiver hook 70 upon operation of the motor, the end of the worm pinion occupying said smooth portion of the worm socket at the end of said extending movement, to be in position to again receive the worm socket on counter-rotation of 75 the motor shaft.

8. In combination with a telephone circuit including a plurality of receivers of other telephones, a local receiver hook and a transmitter, an extensible plunger arranged to lift the hook to the talking position, a motor having a connection with said plunger for extending the plunger on the initial rotation of the motor shaft, a short circuiting means in connection with the 80 transmitter for producing sounds in the receivers of said other telephones on the continued operation of the motor, a source of electrical energy in circuit with the motor, a relay including a contact and an armature 85 arranged to close the motor circuit upon energization of the relay, and a contact in circuit with the relay and a portion of the source of electrical energy, the relay being energized upon closure of the contact. 95

9. In a burglar and fire alarm, the combination with a telephone circuit including a receiver hook and a transmitter, a motor, an extensible plunger in contact with the receiver hook and arranged to raise the hook 100 to the talking position upon operation of the motor, a short circuiting device in connection with the transmitter and actuated in the operation of the motor to issue a warning to a central station without making a 105 local alarm, a source of electrical energy in circuit with the motor, a relay in circuit with a portion of said source of electrical energy and arranged to close the motor circuit upon energization of the relay, and a 110 contact in the relay circuit, arranged to be closed upon the entrance of an intruder, to energize said relay and render said motor operative and issue the warning without the knowledge of the intruder. 115

10. In a burglar and fire alarm, the combination with a telephone instrument including a receiver and transmitter, of means attached to the instrument for issuing a warning to a central station without disturbing the operating function of the telephone instrument, said means including an extensible member in contact with the receiver hook, a motor arranged upon operation to move the extensible member and raise said 120 hook to the talking position, means for short circuiting the transmitter at regular periods actuated upon operation of the motor, a source of electrical energy for operating the 125 motor, a relay controlling the closure of the 130

motor operating circuit, a contact controlling the operation of the relay, and means for short circuiting the receiver when the motor is in operation.

5 11. In a burglar and fire alarm, a contact carrying member including a gear having sets of insulated signal contacts on one side

throughout the circumference of the gear to sound an alarm, and other sets of contacts insulated on the other side of said member,¹⁰ occupying a part of the circumference of said member and arranged to produce a ringing signal.

LE ROY STEWART FOLTZ.
